CLAIM

The ornamental design for sporting equipment accessory holder, as shown and described.

DESCRIPTION

FIG. 1 is an isometric view of a sporting equipment accessory holder showing my design.

FIG. 2 is a top view thereof;

FIG. 3 is a perspective view thereof; and,

FIG. 4 is a side view thereof.

The broken lines shown in the figures are included for the purpose of illustrating portions of the sporting equipment accessory holder and form no part of the claimed design.
